UNITED STATES PATENT OFFICE.

THEODORE F. UHLEMANN, OF NEW YORK, N. Y., ASSIGNOR TO NICHOLAS POWER COMPANY, OF NEW YORK, N. Y., A CORPORATION OF DELAWARE.

FRAMING MECHANISM FOR MOVING-PICTURE MACHINES.

1,351,814.

Specification of Letters Patent.

Patented Sept. 7, 1920.

Application filed November 29, 1918. Serial No. 264,686.

To all whom it may concern:

Be it known that I, THEODORE F. UHLEMANN, a citizen of the United States, and a resident of the city, county, and State of New York, have invented new and useful Improvements in Framing Mechanism for Moving-Picture Machines, of which the following is a specification.

This invention relates to improvements in framing mechanisms for moving picture machines in which the intermittent sprocket is bodily shifted with relation to the projection aperture to correspondingly adjust the film to bring its individual pictures into registration with the aperture.

More particularly the present invention comprises an improvement over the framing mechanism shown and described in Letters Patent Nos. 826,112 and 1,184,126, granted to Nicholas Power on July 17, 1906 and May 23, 1916, respectively.

In each of these patents the intermittent sprocket and its immediate driving shaft are supported on an independent carriage mounted in the machine frame for vertical adjustment immediately beneath the aperture, and in each case the driving shaft of the intermittent gear is actuated from a shaft on the machine frame having stationary bearings through an intermediate gear so mounted on a movable support as to be maintained in mesh with the gear of the stationary main shaft and the gear on the vertically adjustable carriage.

As framing devices, the structure of these patents has proven satisfactory and has been very largely used in commercial machines. Each, however, is open to certain objections which it is the object of the present invention to correct.

In the framing mechanism shown in Patent No. 826,112 the intermediate gear between the stationary gear and the gear on the framing carriage is supported at the knuckle of a pair of toggle links connected respectively to the stationary shaft and the adjustable shaft. This arrangement maintains a proper meshing engagement of the gears at all times, but is open to the objection that the adjustment of the carriage causes a rotation of the sprocket driving gear about its own axis which alters the time of operation of the sprocket with relation to

the other moving parts of the projection machine.

55

In the framing mechanism shown in the Patent No. 1,184,126 the intermediate gear is independently supported in a supplemental carriage which is adjusted simultaneously with the framing carriage but to a less extent, to thereby avoid the rotative movement of the sprocket. In this structure, however, the movement of the intermediate gear is not concentric with the two gears which it connects, and therefore the teeth are moved more or less into and out of mesh with each other with consequent wear and lost motion.

In carrying out the present invention I provide an intermediate gear arrangement in which all the gears are maintained in proper meshing relation, but in which they are so relatively shifted in the framing movement as to maintain the driving shaft of the intermittent gear against rotation, so that the synchronous operation of the intermittent sprocket and the other elements of the film feed is not disturbed.

In the accompanying drawings I have illustrated my invention as applied to a moving picture machine of the type shown in the patent to Nicholas Power, No. 1,184,126 referred to above, and have illustrated only so much of the moving picture machine structure as is necessary to an understanding of the framing mechanism.

In the said drawings, Figure 1 is a side elevation of a moving picture machine equipped with my improved framing mechanism with certain parts shown in section;

Fig. 2 is a similar view of a portion of Fig. 1 showing a different adjustment of the framing mechanism; and

Fig. 3 is a similar view of a modification. Referring to the drawings, 1 indicates the frame of the machine which is supported in the usual manner, the upper and lower sprockets 2 and 3, respectively, of which are continuously rotated from the main driving shaft 4 to feed the film into and out of the machine.

The film, which is indicated at 5, is intermittently fed past the projection aperture 6 where it is exposed for projection in the usual manner by an intermittent sprocket 7 whose

shaft bearings are supported in the vertically adjustable framing carriage 8, all of which parts may be identical with those disclosed in the above mentioned patent to 5 Nicholas Power.

The sprocket 7 is intermittently operated by an intermittent couple, not shown, but which may be of any approved design, for instance that disclosed in the above mentioned patent, from a driving shaft 9 also mounted in the carriage 8. The shaft 9 is continuously driven from a main gear 10 supported on the machine frame and operated by suitable gearing from the main 10 shaft 4. The shaft of the gear 10 is stationarily supported, while the shaft 9 is mounted for vertical adjustment in a right line, and the intermediate gearing for effecting the continuous rotation of the shaft 9 15 from the gear 10 constitutes the novel feature of my invention. This intermediate gearing comprises a gear 11 meshing with the gear 10 and supported at the end of a link or swinging bracket arm 12 having its 20 bearing on the shaft of the gear 10 so that the teeth of the gear 11 will be at all times maintained in proper mesh with the teeth of the gear 10. The gear 11 drives a similar gear 13 whose shaft is carried at the end of 25 a link 14 supported at one end upon the shaft of the gear 11 and at the other end by a third link 15 swung from the shaft 9; the links 12, 14 and 15 forming an articulated connection between the shaft 9 and the 30 shaft of the gear 10. This connection allows the gears 11 and 13 to assume various relative positions but maintains their teeth in constant mesh with each other and also maintains the gear 11 in mesh with gear 10 and 35 gear 13 with the driving pinion 16 on the end of the shaft 9, so that the rotative movement of the gear 10 will be transmitted without interruption to the pinion 16, regardless 40 of the movement of the carriage 8.

45 The mechanism so far described, while sufficient to maintain the driving connection during the framing adjustment, may cause an independent rotative movement of the shaft 9 due to the turning of the gears 50 11 and 13 on their axes when the framing carriage is shifted. To prevent this I provide means for regulating the extent of movement of the axes of the gears 11 and 13 so that the rotative movement of the shaft 55 9 which would be produced by the rotation of one of the intermediate pinions about the axis of the gear which drives it will be compensated for by an opposite movement of the other intermediate gear about the axis 60 of its driving gear.

As shown in Figs. 1 and 2, this means consists of a guide bracket 18 attached to the side of the machine frame adjacent the path of travel of the framing carriage, the 65 bracket having a cam slot 19 which embraces

the end of the shaft on which the gear 13 is mounted, thereby causing the shaft of the gear to shift transversely as well as vertically when the carriage is adjusted. The shape of the cam slot for each particular 70 machine may be readily calculated so as to cause the relative movement of the two gears about their axes to compensate for each other and also for the movement of the gear 13 about the axis of the pinion 16. 75

It is of course to be understood that the accompanying drawing is not drawn to scale, although the cam shown is a close approximation of that required in actual practice.

It will also be understood that the three-link connection between the shaft 9 and the stationary driving shaft constitutes a connection which may be described as of universal flexibility as distinguished from the two-link connection shown in the Power 85 Patent No. 826,112, that is, in adjusting the shaft 9 the several links would not necessarily have the same relative movement for each adjustment (except for the cam slot 19) but either joint might take all the movement, or the total movement may be divided in any proportion between the two joints according to which presents the greatest friction. If, for instance, all the movement took place at the axis of the gear 11, that 95 gear would be rotated, on lowering the framing carriage from the position shown in Fig. 1 to that shown in Fig. 2, in a counter-clockwise direction, which movement would produce an equal clockwise movement of the 100 gear 13, which would be transmitted to the pinion 16 and interfere with the synchronous operation of the film feed and shutter. On the other hand, all the movement might take 105 place at the axis of the pinion 13, the pinion 11 then serving to all intents and purposes as a stationary gear.

In this case the framing movement from the position shown in Fig. 1 to that shown in Fig. 2 will cause a rotation of the pinion 13 110 about its own axis in a counter-clockwise direction, thereby destroying the synchronism of the parts by a retarding instead of an advancing movement to the pinion 16. By means of the cam slot 19 the path of movement of the floating gear 13 is so controlled as to cause a portion of the movement to take place at each of the joints in such definite proportions that the two compensate for each other and also for the slight movement of the gear 13 about the axis of the pinion 16, and the pinion is neither advanced nor retarded. 115

In Fig. 3 I have shown a modified arrangement for controlling the relative movement of the two intermediate gears. As here shown, the arrangement of the driving gears 10, 11, 13 and 16, and their supporting links and brackets, is the same as in the preferred construction, but instead of using a 13

stationary guide coöperating with the shaft of the gear 13 I employ a movable cam 20, here shown as a plate attached to the framing carriage and extending toward the front 5 of the machine in position for its cam slot 21 to embrace the spindle of the gear 11. The gear 11 will thus be raised and lowered with the carriage but to a less extent, depending upon the degree of inclination of 10 the cam slot, which will be calculated so as to properly proportion the required movement between the two joints of the articulated connection to maintain the shaft 9 stationary during the framing movement.

15 It will of course be understood that other means may be employed to guide the shifting pinions in their proper paths of movement. It will also be understood that various other modifications may be made in the 20 structure without departing from the spirit of the invention and the scope of the appended claims.

I claim:

25 1. In a framing mechanism for moving picture machines, the combination of a driving sprocket for the film, an adjustable support for said sprocket, a driving gear for said sprocket having a fixed axis of rotation, gears for transmitting the rotation of said 30 fixed gear to said sprocket, means for maintaining the center of said gears at fixed distances from each other, and means for controlling said gear connection to prevent rotative movement of said sprocket from the 35 movement of its support.

2. In a framing mechanism for moving picture machines, the combination of a feed sprocket for the film, an adjustable support therefor, a driving member for actuating 40 said sprocket having a fixed axis of rotation, intermediate power transmitting devices between said member and said sprocket for effecting the rotation thereof, means for supporting said intermediate devices comprising 45 links pivoted to said support and the axis of said stationary driving member, respectively, and means for controlling said intermediate power transmitting devices to maintain said sprocket against rotation from 50 the movement of its support.

3. In a framing mechanism for moving picture machines, the combination of a carriage mounted for adjustment with relation 55 to the film aperture to frame the picture, a feed sprocket supported on said carriage, means for operating said feed sprocket comprising a gear having a stationary axis of rotation, a gear on said carriage, a power transmitting connection between said gears 60 comprising a gear mounted for movement independently of said carriage and with its axis of rotation maintained at an equal distance from the axis of said stationary gear, and means for controlling said power transmitting connection so as to prevent rotation 65

of said sprocket from the movement of said support.

4. In a framing mechanism for moving picture machines, the combination of a carriage mounted for adjustment with relation 70 to the film aperture to frame the picture, a feed sprocket supported on said carriage, means for operating said feed sprocket comprising a gear having a stationary axis of rotation, a gear on said carriage, a power 75 transmitting connection between said gears comprising a gear mounted for movement independently of said carriage and with its axis of rotation maintained at an equal distance from the axis of said carriage supported gear, and means for controlling said power transmitting connection so as to prevent rotation of said sprocket from the movement of said support.

5. In a framing mechanism for moving 85 picture machines, the combination of a carriage mounted for adjustment with relation to the film aperture to frame the picture, a feed sprocket supported on said carriage, means for operating said feed sprocket comprising a gear having a stationary axis of rotation, a gear on said carriage, a power 90 transmitting connection between said gears comprising a gear mounted for movement independently of said carriage both vertically and horizontally, and means for guiding 95 said gear in its movement so as to prevent rotation of the sprocket from the movement of its support.

6. In a framing mechanism for moving 100 picture machines, the combination of a film feeding sprocket, an adjustable support therefor, a gear having a stationary shaft for rotating said sprocket, means for transmitting the movement of said gear to said 105 sprocket comprising a plurality of gears intermediate said gear and said sprocket, means for supporting said gears for movement independently of said carriage, and means for guiding said gears in their movement so as to prevent rotation of the 110 sprocket from the movement of its support.

7. In a framing mechanism for moving picture machines, the combination of a feed sprocket, an adjustable support therefor, a 115 main driving gear having a fixed axis of rotation for driving said sprocket, a plurality of intermediate gears between said sprocket and said main driving gear, a pivoted support for one of said gears having its 120 axis of rotation coincident with the axis of said stationary gear, a pinion on said adjustable support, a gear intermediate said pinion and said last mentioned gear, said gear being mounted on a swinging support 125 having its axis of rotation coincident with the axis of said pinion, and connections between said two supports for maintaining the gears carried thereby in mesh.

8. In a framing mechanism for moving 130

picture machines, the combination of a feed sprocket, an adjustable support therefor, a main driving gear having a fixed axis of rotation for driving said sprocket, a plurality of intermediate gears between said sprocket and said main driving gear, a pivoted support for one of said gears having its axis of rotation coincident with the axis of said stationary gear, a pinion on said 10 adjustable support, a gear intermediate said pinion and said last mentioned gear, said gear being mounted on a swinging support

having its axis of rotation coincident with the axis of said pinion, connections between said two supports for maintaining the gears carried thereby in mesh, and means for controlling the movement of said swinging supports so as to prevent rotative movement of said sprocket on the movement of its support. 15

Signed at New York city in the county of New York and State of New York this 14 day of October 1918.

THEODORE F. UHLEMANN. 20
